(57) CLAIM

The ornamental design for a garment, as shown and described.

DESCRIPTION

FIG. 1 is a front perspective view of a new design for a garment.

FIG. 2 is a rear perspective view of the design of FIG. 1.

FIG. 3 is a front view of the design of FIG. 1.

FIG. 4 is a rear view of the design of FIG. 1.

FIG. 5 is a right side view of the design of FIG. 1.

FIG. 6 is a left side view of the design of FIG. 1.

FIG. 7 is a bottom view of the design of FIG. 1; and,

FIG. 8 is a top view of the design of FIG. 1. The broken lines in FIGS. 1, 2, 4, 5, 6, 7, and 8 represent portions of the garment that form no part of the claimed design.
